DESIGN FOR A SHADED ADJUSTABLE EGG CANDLER

Richard Hollwedel, Long Island City, N. Y.

Application April 26, 1934, Serial No. 51,523

Term of patent 7 years

To all whom it may concern:

Be it known that I, RICHARD HOLLWEDEL, a citizen of the United States, residing at Long Island City, in the county of Queens, and State of New York, have invented a new, original, and ornamental Design for Shaded Adjustable Egg Canders, of which the following is a specification, reference being had to the accompanying drawing, forming part thereof.

In said drawing, Figure 1 is a top plan view of a shaded adjustable egg candler;

Figure 2 is a side elevation thereof, and

Figure 3 is a front view of the shaded adjustable egg candler showing my new design.

I claim:

The ornamental design for a shaded adjustable egg candler, as shown.

RICHARD HOLLWEDEL.
